UNITED STATES PATENT OFFICE.

JAMES S. PERROW, OF ALTAVISTA, VIRGINIA, ASSIGNOR OF ONE-THIRD TO JOSEPH E. BROCHU, OF ESMONT, VIRGINIA.

FURNACE.

1,390,309.

Specification of Letters Patent Patented Sept. 13, 1921.

Application filed July 16, 1919. Serial No. 311,330.

To all whom it may concern:

Be it known that I, JAMES S. PERROW, a citizen of the United States, residing at Altavista, in the county of Campbell and 5 State of Virginia, have invented a new and useful Furnace, of which the following is a specification.

The device forming the subject matter of this application is a furnace, adapted to be 10 used in connection with a barn or other structure wherein tobacco is cured.

The invention aims to provide a furnace made simply and inexpensively out of castings and other materials which are readily 15 obtainable or readily made.

The invention aims to provide novel means for mounting the grate, to provide novel means for controlling the draft door, to improve the construction of the casing, 20 and, particularly, to provide a novel crown in the casing; and, generally, to improve and to enhance the utility of devices of that type to which the invention appertains.

With the above and other objects in view, 25 which will appear as the description proceeds, the invention resides in the combination and arrangement of parts and in the details of construction hereinafter described and claimed; it being understood that, within 30 the scope of what is claimed, changes in the precise embodiment of the invention shown can be made without departing from the spirit of the invention.

In the accompanying drawings:—

35 Figure 1 shows in perspective, a device constructed in accordance with the invention, the casing having been removed; Fig. 2 is a transverse section of the complete furnace looking toward the front; Fig. 3 is a perspective view showing one of the crown sections; Fig. 4 is a longitudinal section of the complete furnace; Fig. 5 is a perspective showing one of the grates; Fig. 6 is a sectional detail showing one of the 40 anchoring bolts for the front plate of the furnace; and Fig. 7 is a fragmental vertical section similar to Fig. 4 but illustrating a modification.

In carrying out the invention, there is 50 provided a front plate 1 having a curved top 2. The numeral 3 marks the stoke door carried on the front plate 1 by hinges 4 and adapted to swing open, horizontally. The door 3 is supplied with a latch 5 adapted to

cooperate with a keeper 6 on the front plate 55 1, the door carrying a handle 7.

Located below the stoke door 3 is a combined draft and ash door 8, mounted to swing vertically on hinges 9 assembled with the front plate 1. The numeral 10 denotes 60 a curved prop provided with teeth 11 on its lower edge. The prop 10 extends outwardly through an opening 12 in the door 8. The door 8 is supplied with outstanding ears 14 carrying a pivot pin 15 on which the prop 65 10 is mounted to swing vertically. The prop 10 is provided at its outer end with a grip 16. The grip 16 serves as a means for manipulating the prop 10, and serves, also, as a handle whereby the door 8 may be swung 70 vertically on its hinges 9. When the door 8 has been opened to any desired extent, either for the purpose of creating a draft, or for the removal of ashes, the teeth 11 on the prop 10 may be engaged with the front 75 plate 1 at the lower edge of the opening 17 for which the door 8 constitutes a closure. The front plate 1 is provided with openings 18.

The numeral 19 denotes a rectangular 80 frame provided at its ends with inwardly projecting flanges 20. The side portions of the frame 19 are connected at an intermediate point by a cross bar 21 including a horizontal body 22 and an upstanding flange 23. 85 The rear end of the frame 19 is supplied with an outwardly projecting lip 25. Securing elements 24, which may be bolts, unite the forward end of the frame 19 with the front plate 1. The frame 19 may be supported at its rear end and at its sides, on posts 26, formed independently of the frame. The posts 26 may be omitted if desired. The numeral 27 designates a thimble carried by a plate 28 having a rim 29, the rim being 90 connected by securing devices 30 to the lip 25 of the frame 19. The thimble 27 enters one end of a flue 31, the flue and the thimble being supplied with an eye 32, adapted to receive a wire 33 or the like, which serves to 95 hold the flue on the thimble. Grate sections 34 are provided, the outer ends of the grate sections being supported on the flanges 20 at the ends of the frame 19, the inner ends of the grate sections being supported on the body portion 22 of the cross bar 21, the flange 23 of the cross bar 21 being received 100 between the inner ends of the grate sections. 105

The invention comprises a casing, including sides 35 and a rear end wall 36, the sides and the rear end wall preferably being made of bricks. The upper edge of the rear end wall 36 is curved to correspond to the curved top 2 of the front plate 1. The lip 25 on the frame 19 is supported in the rear end wall 36; and, thus, the frame 19 is upheld at its rear end, the forward end of the frame being connected, as aforesaid, by means of the securing elements 24, to the front plate 1. The rim 29 of the plate 28 which carries the thimble 27 is embedded in the brick work of the rear end wall 36. The posts 26 rest against the sides 35 and against the end wall 36 of the brick work portion of the casing.

The casing portion of the furnace includes a crown, made up of a plurality of arched sections 37 disposed end to end, each section being provided at one end with an offset flange 38 receiving the end of an adjoining section. The flange of the rearmost section of the curved top overlaps rear end wall 36, as shown at 39, the end of said section abutting against the rear end wall as shown at 40 so that the crown, considered as an entity, cannot slide rearward. The foremost arched section of the crown rests on the curved top 2 of the front plate 1, as shown at 41. The sections 37 of the crown are provided with flat outwardly extended side members 42 resting on the upper edges of the sides 35. These side members 42 serve not only to support the arched sections 37 of the crown, but, also, serve as protectors or guards for the upper edges of the brick work sides 35. The side members 42 coöperate with the sections 37 to define shoulders 43, which, coacting with the inner surfaces of the sides 35, prevent the sections 37 from moving transversely of the furnace.

In the openings 18 of the front plate 1, tie bolts 44 are located, the heads 45 of the tie bolts engaging the front plate 1, the tie bolts extending rearwardly into the brick work which forms the sides 35. Washers 46 are mounted on the tie bolts 44 and bear against the brick work, nuts 47 being threaded on the ends of the bolts to coöperate with the washers 46. The tie bolts 44 are embedded in the brick work of the sides 35 as the sides are being built up and form a secure anchorage for holding the front plate 1 in place.

In Fig. 7 of the drawings, parts hereinbefore described have been designated by numerals previously used, with the suffix "a." In Fig. 7, the thimble 27^a is a simple tube, the plate 28 and the rim 29 of Fig. 1 being omitted, the thimble being merely embedded in the brick work of the rear end wall 36^a.

Having thus described the invention, what is claimed is:—

1. A furnace comprising a front wall; a casing including a rear end wall and side walls; a rectangular frame including end members, one end member having an outstanding lip mounted in the rear end wall, the end members being provided with inwardly extended flanges, the side portions of the frame being connected by a cross bar including a horizontal body and an upstanding flange; grate sections within the frame, the outer ends thereof being supported on the flanges of the end members, the inner ends thereof being supported by the body of the cross bar and being separated by the flange of the cross bar; means for securing the other end member of the frame to the front wall; and a crown comprising arched sections extended between the front wall and the rear end wall, the intermediate crown sections having transverse flanges receiving the adjacent end of an adjoining section; the crown sections being provided with laterally extended side members resting on the upper edges of the side walls.

2. A furnace comprising a front wall; a casing including a rear end wall and side walls; a crown extended between the front wall and the rear end wall and supported on the side walls; a grate-carrying frame secured at its forward end to the front wall and provided at its rear end with an outstanding lip mounted in the rear end wall; a plate provided with a thimble, and including a circumferential rim, the rim being mounted in the rear end wall and being supported on the lip; and means for securing the rim to the lip.

In testimony that I claim the foregoing as my own, I have hereto affixed my signature in the presence of two witnesses.

JAMES S. PERROW.
